UNITED STATES PATENT OFFICE.

GUSTAF GARANSSON, OF ZEANDALE, KANSAS.

HAY-DERRICK.

SPECIFICATION forming part of Letters Patent No. 761,159, dated May 31, 1904.

Application filed October 30, 1903. Serial No. 179,206. (No model.)

To all whom it may concern:

Be it known that I, GUSTAF GARANSSON, a citizen of the United States, residing at Zean-dale, in the county of Riley and State of Kan-sas, have invented a new and useful Hay-Der-rick, of which the following is a specification.

This invention relates to hay-derricks; and the object thereof is to provide an improved form of hay-derrick in which the elements are so arranged and proportioned as to give a maximum of strength to a minimum of weight and to provide novel mechanism whereby the load may be hoisted and the derrick swung upon its base to bring the load into position for deposit.

A further object of the invention is to pro-vide an improved form of folding derrick the boom of which may be lowered with but lit-tle difficulty when it is desired to trans-port the derrick from place to place and raised and secured with equal facility when it is desired to put the derrick into operation.

With the objects above mentioned and oth-ers in view, which will appear when the in-vention has been fully disclosed, the same con-sists in the novel construction and combina-tion of parts of the hay-derrick hereinafter described, illustrated in preferred form in the accompanying drawings, and having the novel-features thereof particularly set forth in the appended claims.

In the drawings, Figure 1 is a view in ele-vation of the derrick in position for operation. Fig. 2 is a view of the derrick with the boom released and lowered for transportation. Fig. 3 is a view in rear elevation of the lower por-tion of the derrick. Fig. 4 is a plan view of the folding boom-brace. Fig. 5 is a similar view of the boom. Fig. 6 is a plan view of the drum at the base of the mast. Fig. 7 is a detail view of the mast-supporting ring; and Fig. 8 is a detail view in vertical section at the bottom of the mast, showing the form of bearing used for supporting the mast.

Referring to the drawings, in which corre-sponding parts are designated by similar char-acters of reference throughout, F designates the ground-frame or base of the derrick, which consists of side bars 11 and a plurality of cross-bars 2. The middle cross-bar is broader

and heavier than the end bars, and on it is mounted a plate 3, having a central opening 4 to receive a pivot-pin 5, which is fixed in the center of the mast 6 at the lower end thereof. A plate 7 is attached to the bottom of the mast in order to reduce the friction of rota-tion of the mast upon the plate 3.

In order to hold the mast in upright posi-tion, a plurality of oblique braces 8 (in this instance four in number) are attached at their lower ends to the side bars 1 of the frame F and are connected at their upper ends with a split ring 9 of the character illustrated in Fig. 7, which encircles the mast somewhat above the middle. The brace members 8 are 65 preferably connected by crossed stay-rods 10, as shown in Figs. 1 and 2.

The mast may be of any suitable length and will preferably be square in cross-sec-tion, tapering from the middle, where its di-ameter is greatest to both ends. Blocks will of course be secured upon the mast where it is encircled by the ring 9 in order to afford a continuous bearing-surface for engagement with the ring. The mast may be made of a 75 single stick of timber of suitable dimensions or may be made of a plurality of sections se-cured together in any suitable manner.

At the lower end of the mast a drum is formed of horizontal members 11 and vertical members 12, arranged as shown in Figs. 1 and 6. This drum forms in connection with a cord 13, which may be attached to any one of the vertical members 12, means whereby to turn the mast through any desired angle 85 when the load is hoisted.

The boom, which is pivotally mounted at the top of the mast, consists of two members 14, secured at their lower ends by a bolt 15, which passes through the members 14 and 90 through the top of the mast and connected at their upper ends by means of a plurality of bolts 16, 17, and 18. The bolt 16 forms the shaft on which turns a small pulley 19. The bolt 17 extends through a spacing-block 20, 95 by which the two boom members 14 are sepa-rated to the desired distance, and the bolt 18 forms the pivotal connection between the brace and the boom members. The outer end of the boom is strengthened by means of 100

a short truss comprising stay-rods 21, connected at one end with the extremities of the members 14 and connected at their other ends with the members 14 below the bolt 18, the 5 stay-rods being supported at their middle points by a member 22 rising from the bolt 18.

The boom-brace consists of two converging members 23, pivotally supported upon a bolt 24, which passes through said members 23 10 and through the mast, and two converging members 25, having beveled inner ends supported on the bolt 26 in members 23 and connected with the boom by the bolt 18, already mentioned. The members 23 are strengthened 15 by cross-rods 27 and oblique rods 28, the former being adapted to serve as rungs when it is necessary for a person to climb out upon the brace. In order to secure the boom members in extended position, a bolt 29 is 20 provided in the outer ends of the members 23 and a block 29^a is placed adjacent thereto for contact with the beveled ends of the members 25.

The means for hoisting the boom and boom-brace into operative position comprises a rope 30, attached at one end to a bracket 31, mounted in the lower end of the two members 25 and passing over pulleys 32 and 33, mounted in said bracket 31 and in a bracket 34, mounted 25 in the upper end of the mast. The free end of the rope 30 extends down the mast a short distance and may be wound upon one of the cleats 35, provided at intervals on the mast and on the oblique braces to afford means 30 for climbing the derrick when necessary.

The load-hoisting rope has one end attached to a swivel mounted on the boom at its upper end and passes from the swivel downward under a traveling pulley 37, to which 40 the lifting-tongs may be attached, and passing thence upward over the pulley 19 in the upper end of the boom downward over a pulley 39 in a bracket 40, projecting from the mast on the side opposite the boom. The 45 hoisting-rope passes from the pulley 39 downward and under a pulley 41, attached to the end of the rope 13, its outer end having a whiffletree 42 attached thereto to afford means for hitching a draft-animal to the hoisting-rope.

As explained in the preceding paragraph, the rope 13 is attached to one of the vertical members 12 of the drum at the base of the mast and serves when the load is hoisted on the 55 derrick to effect the rotation of the mast with all the structures carried thereby. To guide the movement of the rope 13, a guide-pulley 43 is suspended on a rope 44 and is secured by a short rope 45, connecting the pulley 60 with the frame F.

When the derrick is in operation, the load will be secured by tongs or any other convenient means and suspended from the traveling pulley 37. Power will then be applied to 65 the hoisting-rope by driving a draft-animal

outward away from the derrick-frame, and the tension upon the hoisting-rope will lift the load and at the same time by pulling against the pulley 41 will exert sufficient tension on the rope 13 to turn the mast and swing 70 the load around to the desired point for deposit.

When it is desired to transport the derrick from one place to another, the bolt 29 must be withdrawn from engagement with the members 23 and 25 forming the boom-brace, and the rope 30 must be unwound from its cleat 35 to allow the brace members to fold upon each other and let the boom swing down into the position shown in Fig. 2. When in this 80 position, the derrick may be conveniently transported, and when the destination has been reached the brace members may be hoisted into proper position by pulling upon the rope 30, and when the boom has been 85 raised to proper height the rope 30 will be wound upon one of the cleats 35 and the bolt 29 placed in position to secure the brace members 23 and 25 in position, as shown in Fig. 1.

The bevel at the inner ends of the members 25 is so formed that when the boom is raised into operative position the said beveled ends of the members 25 contact with the block 29^a before the members 23 and 25 are brought 95 into perfect alinement. The brace is thus characterized by a very obtuse angle when in operative position, and the strain imposed upon the brace when a load is hoisted upon the boom tends to force the joint of the brace 100 downward. The tendency of the brace to fold by the downward movement of the joint is directly opposed by the rope 30, attached to the bracket 31 and passing over the pulleys 32 and 33. Consequently the bolt 29, extending 105 through the adjacent ends of members 23 and 25, is relieved of any excessive strain and there is no tendency of the members to buckle upward when a heavy load is hoisted by the derrick.

In the construction of the derrick as above described any suitable materials for the different parts may be employed and the proportions and mode of assemblage of the several elements may be varied without departing 115 from the spirit of the invention or sacrificing any of its advantages. I therefore wish it understood that I do not limit myself to the particular form of the parts illustrated or to the specified mode of arrangement, but reserve the right to make such changes therein as lie within the scope of the appended claims.

Having thus described the construction and operation of my invention, what I claim as new, and desire to secure by Letters Patent, 120 is—

1. The combination in a structure of the class described, of a mast, a boom pivotally mounted on the mast, a folding brace for said boom comprising two pivotally-connected 130

- members so arranged that the extension of said members into a position of perfect alinement is positively prevented, and means for locking said brace members in extended position. 5
2. The combination in a structure of the class described, of a rotatable mast, load-supporting mechanism carried by said mast, a drum mounted on said mast and comprising 10 two pairs of frames, the frames in each pair being parallel and one pair of frames being disposed perpendicular to the other pair of frames, and a rope secured to said drum for imparting rotative movement to said mast. 15
3. The combination in a structure of the class described, of a mast, a boom mounted on said mast, and a folding brace for said boom, said brace consisting of two pivotally-connected members, the pivoted end of one of 20 said members being beveled and the other member including a block having a beveled face for contact with the beveled end of the first member to limit the movement of said member and prevent its extension into perfect alinement. 25
4. The combination in a structure of the class described, of a rotatable mast, load-hoisting mechanism carried by said mast and
- including a hoist-rope, a drum on the mast, a rope attached to said drum, and a pulley attached to the rope secured to said drum and traveling on said hoist-rope. 30
5. The combination in a structure of the class described, of a base, a mast pivotally mounted thereon, a boom carried by said mast, a load-hoisting rope carried by said boom, a drum on the mast, a rope attached to said drum, and a pulley mounted on the end of said rope attached to the drum and traveling on said load-hoisting rope. 35
6. The combination in a structure of the class described, of a base, a mast pivotally mounted on said base, a boom carried by said mast, a load - hoisting rope carried by said boom, a drum mounted on the mast, a rope 40 partially wound on the drum, a guide-pulley engaged by said rope, and a pulley attached to the end of said rope and engaging said load-hoisting rope. 45

In testimony that I claim the foregoing as 50 my own I have hereto affixed my signature in the presence of two witnesses.

GUSTAF GARANSSON.
